UNITED STATES PATENT OFFICE.

JAMES M. CHAPPEL, OF DALLAS, TEXAS.

ELECTRIC TIME-SWITCH.

No. 825,111.

Specification of Letters Patent.

Patented July 3, 1906.

Application filed July 24, 1905. Serial No. 271,015.

To all whom it may concern:

Be it known that I, JAMES M. CHAPPEL, a citizen of the United States, residing at Dallas, in the county of Dallas and State of Texas, have invented certain new and useful improvements in Electric Time-Switches, of which the following is a specification.

This invention relates to electric time-switches.

10 The object of the invention is to provide novel means whereby an electric switch may automatically be operated to complete and to break an electric circuit whereby the times of such operations may accurately be predetermined.

Further, the object of the invention is to provide a device for automatically operating an electric switch to complete and to break an electric circuit of such construction that 20 the movable parts of the switch shall be operated positively and shall be securely locked in the positions to which they are moved, thereby preventing accidental displacement of the parts.

25 The invention consists in the construction and arrangement of the parts substantially as hereinafter described and claimed.

In the accompanying drawings one form of embodiment of my idea is shown.

30 In the drawings, Figure 1 is a side elevation of the invention, showing by full lines the positions of the parts when set ready for the automatic closing and subsequent opening of the switch and by dotted lines the positions 35 of the parts after the switch is closed. Fig. 2 is a view of the side opposite to that shown in Fig. 1, the parts being shown in the positions assumed after the switch is opened. Fig. 3 is a side elevation of a part of the 40 frame and the mechanism of a clock having attached thereto means for locking and releasing the switch-operating devices. Fig. 4 is a face view of the parts shown in Fig. 3. Fig. 5 is a detail view of a portion of the locking and releasing mechanism by which the 45 spring for opening the switch is governed. Fig. 6 is a detail view of a part of the means for securing and releasing the spring by which the switch is closed. Fig. 7 is a detail 50 view of the means for attaching the spring by which the switch is opened to the bail for limiting the movement of this spring. Fig. 8 is a perspective view of the device, showing the positions assumed by the parts after the 55 switch has been opened; and Fig. 9 is a de-

tail view particularly showing the positions of the parts when the switch is closed.

In illustrating my invention, I have shown it applied to a simple form of switch consisting of two pivoted arms insulated from each other and corresponding spring-fingers receiving the respective arms to complete a circuit, the arms to be removed from the fingers to break the circuit.

In the drawings, 1 represents the bed-plate 65 of the switch, on which are pivoted the conducting-arms 2 2. Also attached to the bed-plate are the socket-fingers 3 3, the arms and socket-fingers being adapted for connection in the usual way with the wires of a lighting 70 system or the like. The pivoted arms 2 2 are connected by a bar 4 of insulating material, and to this bar is attached a post 5, having joined to it by a pivotal connection the mechanism by which the switch is opened 75 and closed. In order to limit the downward movement of the arms 2 2 in closing the switch, I provide the bar 4 with a projection 6, of wood fiber or other suitable material. The projection is of a length to come into contact with the bed-plate when the arms have assumed positions to make perfect contact with the sockets, preventing further movement which might tend to injure the parts.

The means for opening and closing the 85 switch is connected to the post 5 by a link 7, one end of which is pivoted to the post. The link is slotted for nearly its entire length, and the slot receives a pin extending through an eye near the end of a leaf-spring 8. The link 90 is formed with an opening 9 for the reception of a pin for connecting it to the spring 8 when the device is to be used only for automatically breaking a circuit. The spring 8 is secured at one end to the casing 10 of a clock 95 by the mechanism of which the movements of the switch-operating mechanism are timed and governed.

Mounted on a frame 11 is a standard 12, which standard is located adjacent to the 100 switch. The standard has in it a slot 13, the pivoted bail 14 attached to the spring 8. The bail is free to move up and down in the slot 13, and the upward movement of the bail, and consequently that of the spring 8, is limited by the play allowed the bail in the slot. The bail is attached to the spring 8 near the end thereof by adjusting-screws 15, passing through a plate 16, having an opening for the 105 reception of the spring. The length of move- 110

ment of the spring allowed by the bail may be regulated by adjustment of the screws. Attached to the plate 16 by a screw 17 is a handle 18 for grasping in forcing the spring to 5 a position near the standard, and thus putting the spring under tension. The inner face of the plate 16 has formed with or attached to it a hook-shaped projection 19, as shown particularly in Fig. 5, and this projection is engaged by the hooked end 20 of a trigger-lever 21, pivoted to the standard 12 and extending to a point near the clock mechanism, where it is locked and released by an attachment to such mechanism which will be described 10 hereinafter.

Connected to the post 5 is a bar 22, which in turn is pivotally united with a rod 23, sliding in an opening in the standard 12. The rod 23 has in its lower face a notch 24, (shown 20 particularly in the detail Fig. 6 of the drawings,) which notch is engaged by the end of a trigger-lever 25, corresponding in general form and arrangement to the trigger-lever 21.

A pin 26 is placed in a passage through the 25 standard 12, the passage being at right angles to and intersecting the slot 13 near the outer end of the slot. The pin is of a length to be struck by the head 27 of the rod 23 as the latter is moved toward the standard. The 30 other end of the pin 26 comes into contact with the end of the trigger-lever 25 above the pivot 28 of the latter when pushed by the head 27, forcing one end of the lever into the notch 24 of the rod and bringing the other 35 end into a position to be engaged by a catch by which it is held until it is released by a connection to the clock mechanism.

The pin 26 has an indentation in its lower face, which is adapted to receive the cross-40 piece of the bail when the latter is carried outward by the spring 8.

A spring is arranged between the post 5 and the end of the spring 8, and by this 45 spring when the rod 23 is free to slide in the standard 12 the moving parts of the switch are forced into contact with the spring-sockets, as shown by dotted lines in Fig. 1, closing the switch. In the form of the invention here illustrated I employ a coil-spring 29, one 50 end of which bears against the end of the slot in the link 7 adjacent to the post 5 and the other end of which passes through the other end of this slot and also through eyes in the end of the spring 8, forming a pivot connecting the link and the spring 8.

The trigger-levers 21 and 25 both extend into the casing 10 of the clock, where they are respectively engaged by catches 30 31, carried by springs 32 33, and formed with inclined faces, as shown particularly in Fig. 3 of the drawings.

Connected to the arbor of the hour-hand of the clock mechanism by independent gears and pinions to cause them to rotate simultaneously with and in the same direction as

the hour-hand of the clock are the gears 34 and 35. Each of the gears 34 35 has formed with or attached to it a sleeve 36, having therein a notch 37, and bearing on the end of each sleeve is a pin 38, carried by a shaft extending to the rear face of the clock. The shaft of the gear 34 has on it a hand 39, placed in front of a dial 40 on the rear face of the clock, while that of the gear 35 has a hand 41 placed in front of a dial 42.

The springs 32 and 33 bear against the gears 34 and 35, respectively, and tend to force the sleeves 36 against the pins 38.

In setting the device for an initial operation the switch is opened manually, and as 80 this is done the head of the rod 23 is forced against the pin 26, pressing the latter against the trigger-lever 25. This movement forces one end of the lever into the notch 24 of the rod 23 and carries the other end over the inclined face of the catch 31, which catch is forced by the spring 33 into the position shown in Fig. 3 to lock the lever in place. The handle 18 is then forced inward against the resiliency of the spring 8 and the projection 19 brought into engagement with the hook on the end of the trigger-lever 21. This movement of the handle 18 also placed the spring 29 under tension, the parts being in the positions shown by full lines in Fig. 1. 90 The contact of the projection with the head of the lever 21 depresses the latter throughout its length and brings its rear end over and into contact with the catch 30. In this position all the parts are securely locked and 100 will remain so until the catches are removed from engagement with the trigger-levers. The hands 39 and 41 are next set to point to the hours at which the trigger-levers are respectively to be released. Inasmuch as the gears 105 34 and 35 move in accord with the hour-hand of the clock and as the pins 38 are parallel to the hands 39 and 41, the setting of either hand to point to any hour on its dial will insure the dropping of its pin into the notch of 110 the sleeve against which it bears at the designated hour, thus allowing the spring 32 or 33 to carry its catch away from engagement with the trigger-lever against which it bears. The trigger-lever 25 will be released first, and 115 when this takes place by the movement of the clock mechanism and the connection between the latter and the catch 31 the spring 29 will be freed and will expand and force the switch into a closed position. As the arms 2 120 2 move toward the fingers 3 the pivotal pin connecting the link with the spring 8 will move freely in the slot of the link and when the switch is closed will bear against the outer face of the slot. When the catch 30 is moved 125 from engagement with the trigger-lever 21, the spring 8 operates to open the switch, bringing the parts to the positions shown in Fig. 2. As the switch is thus opened the head of the bar 23 coming into contact with 130

the pin 26 forces the latter against the trigger-lever 25, carrying its end over the inclined face of the catch 31 and into contact with the locking-face of the catch. As the 5 spring 8 moves outward the bail is brought into engagement with the notch in the pin 26, securing the latter and the parts controlled by it against rebound. The switch when it has assumed the position as set forth is securely locked against accidental displacement by jarring or otherwise. By bringing the hook 19, carried by the spring 8, into engagement with the trigger-lever 21 the parts are all set ready for another operation to be 15 started by the clock mechanism at the time indicated by the hands opposite the dials on the rear face of the clock.

If desired, the mechanism may be used only for operating to open a switch which has 20 been closed manually at a predetermined time. When this is desired, the spring 29 is removed from the machine and the pivot connecting the spring 8 with the link is removed from the slot in the latter and a pin is passed 25 through the opening 9 of the link and through the eye near the end of the spring 8. When the parts are thus connected, the arms of the switch have no movement to open or close independently of the spring 8, and the 30 switch will be automatically opened and held open by the spring at the time indicated by the hand 39 on its dial.

Having thus described my invention, what I claim as new, and desire to secure by Letters Patent, is—

1. An electric time-switch comprising a part movable to make and break an electric circuit, two springs both permanently connected to said movable part and each adapted 40 to move it in a direction opposite to that in which it is moved by the other, a clock mechanism, and connections between the clock mechanism and the springs whereby the latter are respectively caused to operate 45 at predetermined times, substantially as described.

2. An electric time-switch comprising a part movable to make and break an electric circuit, two springs each adapted to move 50 the movable part in a direction opposite to that in which it is moved by the other, a connection permanently uniting the movable part of the switch and the two springs, a clock mechanism, and means governed by 55 the clock mechanism whereby the springs are respectively released at predetermined times, substantially as described.

3. An electric time-switch comprising movable contact-arms, a link connected 60 with the arms, two springs connected to the link and each adapted to move the link in a direction opposite to that in which it is moved by the other, triggers for retaining the springs under tension, a clock mechanism, and connections between the clock 65 mechanism, and

mechanism and the triggers whereby the triggers are respectively released at predetermined times, substantially as described.

4. An electric time-switch comprising a movable part of a switch adapted to make and break an electric circuit, two springs both connected to the movable part and each adapted to move it in a direction opposite to that in which it is moved by the other, means permanently connecting the movable part and the springs whereby each spring is rendered capable of operating independently of the other, means for retaining the springs under tension, a clock mechanism, and means operated by the clock mechanism for releasing the springs, substantially as described.

5. An electric time-switch comprising a part of a switch movable to make and break an electric circuit, a slotted link connected to the movable part, a spring connected to 85 the link by a pin entering and free to slide in the slot, a second spring bearing at one end against the first and at the other end against the link, means for retaining the springs under tension, a clock mechanism, 90 and means connecting the clock mechanism and the means for retaining the springs under tension whereby the springs may be released at predetermined times, substantially as described.

6. An electric time-switch comprising a part of a switch movable to make and break an electric circuit, a spring connected with the movable part, a bail attached to the spring, means for governing the movement 100 of the bail, means for retaining the spring under tension, a clock mechanism, and means connecting the clock mechanism and the retaining means, whereby the latter may be operated at a predetermined time, substantially 105 as described.

7. An electric time-switch comprising a part of a switch movable to make and break an electric circuit, two springs connected to the movable part and adapted to move the latter in opposite directions, a sliding rod connected to the movable part, a trigger adapted to engage the movable rod, a clock mechanism, and a connection between the clock mechanism and the trigger whereby the trigger is engaged, and released at a predetermined time, substantially as described.

8. An electric time-switch comprising a part of a switch movable to make and break an electric circuit, two springs connected to the movable part and adapted to move the latter in opposite directions, a sliding rod connected to the movable part, a pin capable of longitudinal movement arranged adjacent to the rod, a bail attached to one of the springs, a trigger engaging the rod, a clock mechanism, and a connection between the clock mechanism and the trigger whereby the latter is released at a predetermined time, substantially as described.

9. An electric time-switch comprising a part of a switch movable to make and break an electric circuit, two springs connected to the movable part and adapted to move the latter in opposite directions, a sliding rod connected to the movable part, two triggers respectively engaging one of the springs and the sliding rod, a clock mechanism, and means for retaining and releasing the triggers comprising springs having catches, rotating sleeves having indentations against which the springs bear, and pins bearing on the ends of the sleeves and adapted to enter the indentations, substantially as described.
10. An electric time-switch comprising a part of a switch movable to make and break an electric circuit, a spring connected to the

movable part, a trigger for retaining the spring under tension, a clock mechanism, and means for retaining and releasing the trigger comprising a catch carried by a spring, a rotating sleeve having an indentation and driven by the clock mechanism, a rod having a pin bearing against the sleeve and adapted to enter the indentation, a hand attached to the rod, and a dial arranged adjacent to the hand, substantially as described.

In testimony whereof I affix my signature in presence of two witnesses.

JAMES M. CHAPPEL.
